UNITED STATES PATENT OFFICE.

CHARLES R. MORI, OF NEW YORK, N. Y.

BASKET.

Application filed October 28, 1925. Serial No. 65,483.

This invention relates to improvements in utensils and vessels such as baskets, flower vases and similar containers and has for its object to provide a simple, efficient and inexpensive basket made from a single sheet metal blank which is cut away in accordance with a novel principle whereby to provide variously shaped designs of baskets and utensils.

10 By means of dies and tools sheet metal blanks of properly cut shapes may be cut progressively and bent so as to shape out various styles of strong yet light baskets and the like for the purpose of providing 15 a container and an under pedestal, the basket being made of open-work, which reduces to a minimum the cost of manufacturing this type of utensil, while at the same time admitting of many beautiful designs and attractive ornamental shapes being given to these utensils.

Another object of the present invention is to provide an inexpensive light yet strong flower vase or fruit basket, ice-cream container and the like capable of being punched out from sheet metal, with slit portions arranged to be struck out and arranged to provide bracing, and sustaining parts for giving outline to a metal basket.

30 In carrying out the details of construction of the present invention I am able to slit a sheet metal blank in such a manner that open-work, latticed baskets can be prepared at very small expense.

35 With the above and other objects in view my invention consists in the combination, arrangement and details of construction disclosed in the drawings and specification, and then more particularly pointed out in the appended claims.

In the drawings, wherein similar reference characters designate similar parts throughout the respective views,

40 Figure 1 is a top plan view of a blank from which one type of basket can be made,

45 Figure 2 is a side elevation of the completed basket,

Figure 3 is a bottom plan view of the basket,

50 Figure 4 is a top plan view of the completed basket,

Figure 5 is a vertical sectional elevation of said basket,

Figure 6 is a side elevation of a modified form of the present invention, 55

Figure 7 is a fragmental top plan view of the modified form of said invention, and

Figure 8 is a bottom plan view of the modified form of the present invention.

The present invention is constructed from 60 any desired material such as sheet metal. A sheet metal part is made preferably into cylindrical form; and slits are formed circumferentially thereon to give outline to any desired shape of arms; in Figure 1 these series 65 of slits define substantially T-shaped arms, having oppositely extending terminals 11, 11^a, and stems 13 having, if desired, enlargements 12; between the radially disposed T-shaped arms are cheeks 10^a, joining a band 70 10 circumscribing the terminals 11, 11^a. The inner ends of arms 11, 11^a and 13 terminate into a central disk shaped base 15, the intervening portions between the series of T-shaped slits being tabs 14, designed to 75 form the body of the container of the basket. When the T-shaped arms are pressed out and shaped into integral parts of the basket slots 18 are formed. When the tabs 14 are struck out they provide slots 17. 80

In operation with the aid of suitable dies, first the T-shaped arms are pressed downwardly to provide the legs that extend radially and downwardly from the horizontally disposed base 15; these legs are the terminals 85 13, while the cross-pieces 11, 11^a are arranged horizontally having their ends interconnected such as by clinching one into the other as illustrated at 19, to provide a sustaining band. These legs and band provide 90 a pedestal of a basket or other utensil. The tabs 14 are bent upwardly preferably so as to flare outwardly, being connected by the cheeks 10^a to the larger band 10, and if desired this band 10 may have its main body 95 portion scolloped out as shown in Figure 2, to enhance its ornamental appearance.

The slits 16^a are formed after bending down the terminals 13 of the T-shaped arms, while the slots 16 remain after pressing away thereout the enlargements 12 of these T-shaped arms. When all the parts have been arranged as illustrated above there has been formed a beautiful basket wherein every slit and bent part is employed to provide a container, a bottom therefor, and an 100 105

under sustaining pedestal, no part of the sheet metal blank having been wasted. The salient characteristic of this basket is that it is made very light, yet strong, ornamental, the metal spared from the container proper being utilized to provide the pedestal, so that no extra material is needed to provide this pedestal.

Other designs of this basket may be provided, one of which styles will now be described. The sheet metal blank preferably cylindrical has the central disk 21; the series of circumferentially disposed radially extending straight spokes or arms 22, and the intervening series of radial arms 24 which may have intermediate enlargements 23, for ornamental effects, these series of arms radiating from the disk 21. Connected to the arms 22 are cross-pieces 27, 27^a, with central bosses 26, for ornamental effect. 28 designates the band which skirts the arms.

In shaping this blank into a symmetrical basket or other utensil there are provided slots 24' between the said arms. When the arms 24 are bent upwardly to be connected to a continuous skirting band reinforcing the arms 22, the remaining straight arms 22 being bent downwardly to provide a pedestal of open-work design and appearance, a basket is produced. The cross-pieces 27, 27^a of the arms 22 are bent into horizontal tabs disposed at an angle to the arms 22, and these cross-pieces are interconnected in any suitable manner such as by clinching these arms as at 33, to provide a cylindrical base for supporting the pedestal. When the arms are bent upwardly or downwardly slots 31, 32 are provided so that the resultant basket is of open-work design and finish. The difference between the form shown in Figure 1-5 and Figures 6-8, of the novel basket is that in the first form the basket rests upon the edge of the cross-pieces of the T-shaped arms; while in the other figures the basket rests upon an extended base formed by bending these cross-pieces upon themselves. And in this second form material is wasted which intervenes between the sets of arms 22, 24. I claim all changes coming within the purview of the appended claims.

What I desire to claim and seek protection on is:—

1. A sheet metal basket consisting of a horizontal base, a container made of lattice work integrally formed upon said base, and a pedestal beneath said base also made of lattice-work formed integrally upon said base.

2. A sheet metal basket consisting of an imperforate base, an integral container formed around said base and consisting of a series of spaced apart arms, and an under pedestal formed integrally upon said base and also consisting of a series of spaced apart arms.

3. A sheet of metal cut away to provide a circumferential series of radially disposed slits having right angular arms, to provide correspondingly-shaped arms, said arms being bent back to provide a circular container having an imperforate base, and a support beneath said container.

4. A sheet metal blank slit to provide a circumferential series of T-shaped outstruck arms, leaving a circumferential series of tabs, and a circumscribing band, said band and tabs being bent to provide an integral container, said arms being bent down to provide a supporting pedestal for said container.

5. A sheet metal blank being slit to provide a circumferential series of separated segmental strips designed to form a band, and an upsettable rim circumscribing said strips, and also to provide an imperforate disk formed concentrically and centrally of said rim, with integral means for connecting both bands with said disk, said integral means, the rim and said segmental strips being bent so as to position the rim above said imperforate disk and to position the segmental strips therebelow whereby a container is provided above said disk and a support therebelow.

6. A sheet metal blank being formed with slits to provide a central imperforate disk, to provide integral radial arms shaped to be bent into a cylindrical basket, said slits also providing integral portions to be bent downwardly for said disk to provide supporting legs.

7. A sheet metal blank being formed with slits extending circumferentially to provide an upsettable interrupted band and a rim circumscribing same, an imperforate disk, and radially disposed arms connecting said rim to said disk, said rim and arms integrally bent so as to provide an open-work basket, and means disposed radially of said disk and bent, together with said interrupted band beneath said disk to provide a support.

8. A sheet metal blank being formed with a circumferential series of slits, each slit defining a T-shaped arm, and intervening bracing portions, said bracing portions being bent upwardly to provide a basket, part of each T-shaped arm being shaped to provide a rim skirting said bracing portions, said arms being bent downwardly to provide a sustaining pedestal.

9. A sheet metal blank being cut away with slits to provide a circumferential series of upsettable arms and a rim integrally joining them, a series of strips intervening between said arms and rim, also formed by said slits, there being an imperforate central disk remaining, said disk, arms and rim being arranged to provide a basket, and said strips being shaped to provide means for supporting said basket.

10. A sheet metal blank being cut with a

series of slits, disposed radially from a circular unslit central base, said slits providing T-shaped arms, the cross portions of which are designed to be intersecured to pro-

vide a shaped band serving as a sustaining base the remaining parts of said arms being bent upwardly from said base to provide a pedestal, while there are portions between said arms bent upwardly from the central base to join the latter to provide a basket.

11. A sheet metal blank being cut away to provide a central horizontal base, to provide slits defining narrow arms, leaving between the series of arms relatively wider tabs, and 15 a continuous band connected to said tabs said tabs and band being shaped to provide a basket, said narrow arms having portions

being interconnected to provide a sustaining pedestal, while the remaining portions of said arms reinforcing said pedestal. 20

12. As a new article of manufacture a basket consisting of a horizontally disposed base, a circumferential series of arms bent respectively, and integrally above, and below said base so as to be disposed in staggered 25 relation to one another; angular integral arms formed upon one set of arms below said base, and shaped to provide a support for said base. The adjoining edges of the last mentioned arms being interengaged. 30

In witness thereof he has hereunto set his hand this 19th day of October, 1925.

CHARLES R. MORI.
